UNITED STATES PATENT OFFICE.

ALFRED G. F. KUROWSKI, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,137,869.

Specification of Letters Patent. Patented May 4, 1915.

Application filed May 13, 1911. Serial No. 626,930.

To all whom it may concern:

Be it known that I, ALFRED G. F. KUROWSKI, a citizen of the United States, residing in borough of Brooklyn, city of New York, in the county of Kings and State of New York, have invented certain new and useful Improvements in Type-Writing Machines, of which the following is a specification.

This invention relates to paper handling devices for typewriting machines.

The object of my invention is to provide an improved gage against which the upper edge of the paper may be gaged when inserted in the machine. I provide improved means for moving said gage toward and away from the printing line on the platen, and, for positively locking said gage where adjusted.

In prior gages, such as disclosed in Patent No. 963,629 of July 5, 1910, the setting of the gage was effected by loosening screws by means of a screw-driver, adjusting the table to which the gage was fixed, and then tightening the screws. If a frequent re-setting of the gage was required, the screws were sometimes only partially tightened, so that the gage could be more readily re-set; but this made the gage sometimes liable to accidental displacement. There was also provided a swivel joint to adjust the lip of the table close to the surface of the platen after adjusting the table forwardly or backwardly. The table was in consequence sometimes susceptible to accidental displacement by being swung down about said pivot.

The present improvements render the gage more easily adjustable, and liability of accidental displacement is avoided. Moreover the necessity of frequent readjustment of the lip to the platen is avoided. The improvements include a stationary paper adjusting tablet with its edge close to the upper surface of the platen, and a paper-aligning gage, arranged to slide upon said stationary part, whereby said gage is moved toward and away from the printing line on the platen. A rotatable shaft having a finger-piece carries pinions which mesh with racks fast on each end of said gage, so that when said shaft is rotated by the operator, the gage is always positively held parallel to the printing line. The gage may be formed as part of a slidable extension of said table and the racks may be formed on said

extension. A thumb-nut is provided which binds said shaft and locks the gage. Thus, the movement, adjustment, and effective locking of the paper alining gage, are readily accomplished by merely turning a knob fixed on said shaft and tightening said thumb nut.

Other objects and advantages will herein-after appear.

In the accompanying drawings, Figure 1 is a general perspective view of the improvements. Fig. 2 is a sectional view of the platen and the paper gage adapted to it. Fig. 3 is a longitudinal section, taken on the line $x-x$ of Fig. 2.

The usual platen 1 is revolvably mounted by its axle 2 on a platen frame 3. A sloping paper adjusting table 4 is fixed above the platen frame and facing the operator, about tangentially to the surface of the platen, being fastened to brackets 5 by screws 6; said screws preferably passing through slotted holes 7 in the table to afford slight adjustment between its bent edge or lip 8 and the surface 9 of the platen; such adjustment being permanent, or at least infrequently made. Said brackets 5 are slidably splined on rod 10, which is in turn fixed rigidly to the platen frame 3.

On the rear side of the table or section 4 is arranged a slidable table or section 11, having a bent projection 12 serving as a gage for the top edges of the sheets, and said slidable table is guided by its edges 13 fitting between the edges 14 of the inwardly bent ears 15 of brackets 5. To keep the surfaces of said tables in contact and prevent rattling, a screw 16 is passed through a hole 17 in table 4, and through a transverse slot 18 in table 11, and threaded into a boss or stud 19 at the back of table 11. A spring member 20 having arms 21 is interposed between table 11 and boss 19 and presses against said table 11, whereby continued contact between said surfaces is insured, without offering too great opposition to the adjustment of the upper section 11.

At the rear of the table a horizontal shaft 22 is rotatably mounted in bearings 23, provided on brackets 5, and preferably passes through a hole 19a in the boss 19 to steady the shaft. Pinions 24 are fixed on shaft 22 to mesh with parallel racks 25 formed at each end of the table 11; so that when shaft 22 is rotated, by turning the knob 26 fixed

at the end thereof, said table 11 is caused to slide transversely and the gage 12 is thus adjusted toward and away from the printing line of the platen 1. By having a pinion at each end of the shaft 22, both ends of the gage 12 are adjusted simultaneously, so the gage always moves parallel to the printing line. The gage 12 having been set, it may be locked by tightening a thumb nut 27, on the threaded end 28 of shaft 22; causing the collar 29, fixed on said shaft, to bind against the bearing 23.

A side gage 30 is provided on table 4. Any suitable means may be used to adjust the entire device longitudinally. Each bracket 5 may be bent backwardly at 31 and upwardly at 32, to form a yoke having bores 33, whereby the bracket is mounted on the rod 10. In said yoke is seated a spring 34 which presses a key 35 into a groove 36 in said rod, whereby the bracket 5 is prevented from turning although the brackets 5 may be shifted along said bar to adjust the table. Notches 37 are formed on the rod 10 and a detent 38 is mounted on one of the brackets 5 to engage said notches. Detent 38 is pivoted on ear 39 of bracket 5, and is formed with a finger-piece 40 to release the bracket for adjustment. A spring 41 may be provided for the detent.

When it is desired to gage a succession of sheets, the first or trial sheet is inserted, and a certain line thereon is brought to register with the printing line on the platen; the gage 12 is then adjusted, by the knob 26, so that it touches the upper edge of the work sheet. The thumb nut 27 is then tightened to lock the gage. Subsequent sheets will be gaged by the gage 12 to agree with the trial sheet.

One of the features of the improvement provided herein, consisting of a stationary section fixed close to the platen and a slideable section which can be extended, is of advantage; since the two sections really constitute one table, the length of which may be varied at will, so that the gage 12 may be adjusted to any position while a complete table extends therefrom to the surface of the platen.

Variations may be resorted to within the scope of the invention, and portions of the improvements may be used without others.

Having thus described my invention, I claim:

1. In a typewriting machine, the combination with a platen, of a paper adjusting table section adjacent to said platen in communication with the delivery portion thereof, a second section having a squaring gage for the leading edge of the sheet, said second section slideable on the first section, a rack provided on said slideable section, a rotatable shaft mounted on a fixed member, and a pinion fixed on said shaft to actuate said

rack to move the slideable section, to provide an adequate supporting surface for use in squaring a work-sheet.

2. In a typewriting machine, the combination with a platen, of a paper adjusting table section fixed adjacent to said platen, a table section having a gage thereon being slideable on said fixed section, a rack provided on said slideable section, a rotatable shaft mounted in bearings on a fixed member, a pinion fixed on the shaft actuating said rack to move the slideable section when said shaft is rotated, a collar fixed on the shaft, and a nut threaded on said shaft to tighten against said bearing and bind said collar against the bearing to prevent rotation of said shaft.

3. In a typewriting machine, the combination with a platen, of a paper adjusting table section adjacent to said platen, a table section having a gage thereon being slideable on the first section, a rack provided on said slideable section, a rotatable shaft mounted on a fixed member, a pinion fixed on said shaft actuating said rack to move the slideable section, and means for locking the shaft against accidental rotation.

4. In a typewriting machine, the combination with a platen, of a paper adjusting table in communication with the delivery portion of said platen, said table having a squaring gage thereon for the leading edge of the sheet mounted to slide toward and away from the printing line of the platen, a rack provided on said table, a rotatable shaft mounted on a fixed member, and a pinion fixed on the shaft engaging with said rack to move said slideable table when said shaft is rotated, to present an adequate supporting surface to a work-sheet being squared.

5. In a typewriting machine, the combination with a platen, of a slideable table having a squaring gage thereon for the leading edge of the sheet mounted to slide toward and away from the platen, a rack, a rotatable shaft mounted on a fixed member, a pinion fixed on the shaft engaging with said rack to move said table when said shaft is rotated, and means for locking the shaft against rotation to maintain said gage where adjusted.

6. In a typewriting machine, the combination with a platen, of a paper adjusting table adjacent to said platen, in communication with the delivery portion thereof, a squaring gage for the leading edge of the sheet slideable toward and away from the printing line of the platen, a rack fast on said gage, a rotatable shaft mounted on a fixed member, and a pinion fixed on the shaft actuating said rack to move the gage.

7. In a typewriting machine, the combination with a platen, of a paper adjusting table section adjacent to said platen, a sec-

ond section having a squaring gage thereon for the leading edge of the sheet, said second section being slideable on said table section, a spring bearing on one of said sections to maintain them in frictional contact, and means for locking said sections together against relative movement.

8. In a typewriting machine, the combination with a revoluble platen, of a paper-adjusting table comprising a fixed section adjacent the platen in communication with the delivery portion thereof, and a section forming an extension of said fixed section, a paper-squaring gage for the leading edge of the sheet provided on said extension opposite the platen and parallel with the printing line on the platen, said extension being adjustable to move the gage toward and away from said printing line, and means to maintain the squaring gage in parallelism during such adjustment, said table and gage being of a length as measured lengthwise of the platen to provide adequate bearing surface for the paper, and to enable the gage to accurately square the paper.

9. In a typewriting machine, the combination with a platen, of an adjustable gage comprising a rack at each end of the gage, and a single shaft to rotate a pair of pinions one in mesh with each of said racks to move the gage.

10. In a typewriting machine, the combination with a table comprising an adjustable alining gage, of means for guiding it at each end to adjust said gage, and a central guide to steady it.

11. In a typewriting machine, the combination with a platen and a sheet-adjusting table arranged over the delivery portion of the platen, of an alining gage to which the leading end of the sheet may be adjusted and by which said sheet may be squared, a finger-piece, and a connection from said finger-piece to said gage to adjust it in parallelism forwardly and backwardly relatively to the printing line on the platen.

12. In a typewriting machine, the combination with a platen and a sheet-adjusting table arranged over the delivery portion of the platen, of an alining gage to which the leading end of the sheet may be adjusted and by which said sheet may be squared, a finger-piece, a connection from said finger-piece to said gage to adjust it in parallelism forwardly and backwardly relatively to the printing line on the platen, and means to hold the gage where adjusted.

13. In a typewriting machine, the combination with a platen and a sheet-adjusting table arranged over the platen, of a gage to which the leading end of the sheet may be adjusted and by which said sheet may be squared, a finger-piece, a connection from said finger-piece to said gage to adjust it in parallelism forwardly and backwardly relatively

to the printing line on the platen, said finger-piece in the form of a rotatable button, and a shaft connected to said button and having means at its ends to connect it to the ends of the gage to cause said ends to move in unison.

14. In a typewriting machine, the combination with a platen, of a fixed paper adjusting table section adjacent to said platen in communication with the delivery portion thereof, and a second section having a squaring gage for the leading edge of the sheet, said second section slideable on said fixed section to extend the distance from said gage to the printing point and extend the table correspondingly, thereby providing an adequate supporting surface for use in squaring a work-sheet.

15. In a typewriting machine, the combination with a platen, of a paper adjusting table section extending from the delivery portion of said platen, a second section having a squaring gage thereon for the leading edge of the sheet, said second section being slideable on said table section toward and from said platen, a rack provided on one of said sections, a rotatable shaft on the other section, and a pinion fixed on said shaft to engage said rack to move the slideable section, to provide an adequate supporting surface for the paper being squared.

16. In a typewriting machine, the combination with a platen, of a paper table composed of an adjusting member fixed adjacent to the delivery portion of said platen, a slideable adjusting member having a squaring gage thereon for the leading edge of the sheet, said slideable member mounted on said fixed member to slide toward and away from the printing line of the platen, a rack fast on one of said members, a rotatable shaft on the other member, and a pinion fixed on said shaft engaging with said rack to move said slideable paper adjusting member to provide an adequate supporting surface for the paper being squared.

17. In a typewriting machine, the combination with a platen, of a paper table composed of an adjusting member adjacent to the delivery portion of said platen, and a gage member to square the leading edge of the sheet, slideable toward and away from the printing line of the platen, a rack fast on one of said members, a rotatable shaft on the other member, and a pinion fixed on said shaft engaging with said rack to move said slideable gage member, to provide an adequate supporting surface for the paper being squared.

18. In a typewriting machine, the combination with a platen, of a fixed paper adjusting table adjacent to the delivery portion of said platen, a member having a squaring gage thereon for the leading edge of the sheet, said member being adjustable

- on said table to move said gage toward and away from the printing line of the platen to provide an adequate supporting surface for the paper being squared, and a hand wheel at the side of said table for adjusting said member.
19. In a typewriting machine, the combination with a platen, of a paper adjusting table adjacent to the delivery portion of said platen, comprising an adjustable edge guide for the paper and a paper squaring gage for the leading edge of the sheet, said gage adjustable on said table and parallel to the printing line of the platen.
- 10 20. In a typewriting machine, the combination with a platen, of a paper adjusting table near the delivery portion of said platen, a slideable section forming a paper squaring gage thereon for the leading edge 20 of the sheet parallel to the printing line of the platen, said gage being movable by a finger piece toward and away from said printing line, and an edge guide for the side edge of the paper, said table together with said slideable section and said edge guide adjustable as a unit in a direction parallel with the platen axis.
21. In a typewriting machine, the combination with a platen, of a paper squaring gage for the leading edge of the sheet parallel to the printing line on the platen and near the delivery portion of said platen, said gage being moved by a finger piece toward and away from said printing line, and an edge guide for the side edge of the paper, said gage and edge guide being connected and together adjustable in a direction parallel with the platen axis to adjust the sheet along the platen.
- 25 22. In a typewriting machine, the combination with a platen, of a paper adjusting table including a paper squaring gage for the leading edge of the sheet, a rack, a pinion mounted on a rotatable shaft, said pinion engaging with said rack to move said gage toward and away from the printing line of the platen, and an edge guide positioned to engage the side edge of the portion of the sheet supported on said table.
- 25 23. In a typewriting machine, the combination with a platen, of a paper adjusting table having an edge guide, a paper squaring gage for the leading edge of the sheet on said table, a rack, and a pinion mounted on a rotatable shaft, said pinion engaging with said rack to move said gage toward and away from the printing line of said platen.
24. In a typewriting machine, the combination with a revolute platen, of a paper adjustment table mounted at the delivery side of the platen and having a gage with which to square the leading edge of the work-sheet, said table presenting an adequate supporting surface for the work-sheet being squared, and manually operable ad-
- justing devices operating respectively adjacent the opposite ends of the gage for effecting adjustment of said gage toward and away from the printing point, said devices connected to operate in unison and positively move both ends of the gage toward or from the platen at the same speed, and thereby maintain the gage parallel with the printing line on the platen.
- 25 25. In a typewriting machine, the combination with a revolute platen, of a paper-adjustment table mounted at the delivery side of the platen and having a gage with which to square the leading edge of the work-sheet, said table presenting an adequate supporting surface for the work-sheet being squared, manually operable means for effecting adjustment of said gage toward and away from the printing point, and means to secure the gage where adjusted.
26. In a typewriting machine, the combination with a revolute platen, of a paper-adjustment table mounted at the delivery side of the platen and having a gage with which to square the leading edge of the work-sheet, said table presenting an adequate supporting surface for the work-sheet being squared, and manually operable means for effecting adjustment of said gage toward and away from the printing point, said table comprising two portions, one of which is movable, and said gage being mounted on said movable portion.
27. In a typewriting machine, the combination with a platen frame and a platen rotatable therein, of a paper table supported by said frame and adjustable longitudinally thereon, a paper-aligning gage adjustable on said table toward and away from the printing point, a rack at each end of said gage, a shaft having pinions meshing with each rack, and means for locking said gage in its adjusted position.
28. In a typewriting machine, the combination with a platen frame and a platen rotatable therein, of a rod fast on said frame parallel with the platen, brackets adjustable along said rod, a paper table carried by said brackets and adjustable therewith for adjusting a work-sheet along the platen, a gage carried by the table for the side edge of the work-sheet, said rod comprising a rack, a detent carried with said brackets to engage said rack and hold the paper table in adjusted position, and a finger-piece for releasing said detent and permitting said adjustment of the table.
29. In a typewriting machine, the combination with a platen, of a paper-adjusting table extending upwardly and rearwardly from the platen and having its forward edge in receptive relation with the delivery portion of the platen, said table comprising a fixed section and an extensible section, racks on the extensible section at the ends thereof,

a rotatable shaft in rear of said table, pinions on said shaft to engage the racks and thereby adjust said extensible section when the shaft is rotated, said extensible section sliding on the fixed section during said adjustment, and means carried by said shaft at a point intermediate said pinions for

holding the table sections together with a yielding pressure.
